UNITED STATES PATENT OFFICE.

PERLEY R. GLASS, OF QUINCY, MASSACHUSETTS, ASSIGNOR TO PEERLESS MACHINERY COMPANY, OF CHARLESTOWN, WEST VIRGINIA, AND NEW YORK, N. Y.

NAILING-MACHINE.

SPECIFICATION forming part of Letters Patent No. 695,428, dated March 11, 1902.

Application filed July 18, 1901. Serial No. 68,714. (No model.)

To all whom it may concern:

Be it known that I, PERLEY R. GLASS, a citizen of the United States, residing at Quincy, in the county of Norfolk and State of Massachusetts, have invented an Improvement in Nailing-Machines, of which the following description, in connection with the accompanying drawings, is a specification, like characters on the drawings representing like parts.

10 This invention relates to power nailing-machines wherein the driver is reciprocated by power; and it has for its object the production of a novel machine of this character in which the driver-reciprocating mechanism is 15 normally held inactive and is rendered active by a mechanism operated upon by the work into which nails or tacks are to be driven when said work is brought into operative position under the driver.

20 The invention also comprises means whereby after the driver has made one complete reciprocation the driver-reciprocating mechanism is automatically thrown out of operation and held in such inactive position until the 25 work has been brought into operative position to have the next nail driven, when the operation is repeated.

I have also provided a rotating hopper to supply tacks or nails to the raceway and 30 per-rotating mechanism, which may be rendered active or inactive, as desired, so that the hopper may be rotated whenever desired and for as long a period as is necessary to fill the raceway with tacks or nails.

35 In the drawings, Figure 1 is an elevation of my improved nailing-machine. Fig. 2 is a section on the line 2 2, Fig. 1. Fig. 3 is a front elevation of a portion of the device. Fig. 4 is a partial view of Fig. 1, showing some of 40 the parts in another position; and Fig. 5 is a vertical central section of the holder; and Fig. 6 is a section on the line x x, Fig. 5.

The framework of the machine is designated by 3, said frame being of the proper shape to 45 support the operative parts of the device and preferably having the apertured projection 4 extending therefrom, by means of which the device may be hung up when not in use.

The frame 3 includes the usual tubular portion 5, in which the driver 6 reciprocates, as

described in my copending applications, Serial No. 34,877, filed October 30, 1900, and Serial No. 40,080, filed December 17, 1900.

The rotary hopper 6' containing the nails or tacks to be used delivers the same to the raceway 7, and the tacks are fed one by one from the raceway into position underneath the end of the driver by the reciprocating pick-off 8, these parts being preferably of the same construction as the corresponding parts in my above-mentioned applications. In this embodiment of my invention the driver-reciprocating mechanism comprises a plate or disk 9, mounted on a suitable shaft 10, supported in the frame and having projecting therefrom an eccentric lug 11, which engages a groove 12 in a cross-piece 13, rigidly secured to the stem of the driver 6, said stem passing at its upper end through a suitable bearing 15, carried by the frame. As the shaft 10 is rotated it will be evident that the driver will be reciprocated to drive the tacks or nails.

The driver-reciprocating mechanism is normally held inactive, but may be clutched to a continuously-rotating shaft 16 when it is desired to operate the same. The said shaft 16 is supported in suitable bearings in the frame of the machine and will have connected thereto the flexible shafting 17, so that the machine may be moved to any desired position during its operation.

The shaft 10 and the shaft 16 are connected together by what I have called a "one-revolution" clutch device—i. e., a clutch device which when rendered active to clutch the two shafts together will be automatically thrown out of engagement after the shafts have made the single revolution. This clutch device is illustrated as comprising the clutch member 18, fast on the shaft 16, and the co-operating clutch member 19, slidably mounted upon the shaft 10, but connected thereto so as to rotate therewith, said clutch member 19 having the usual projections 20', which may be made to engage either corresponding projections (not shown) on the clutch member 18 or may be received in suitable recesses in the clutch member 18, as desired. The clutch member 19 is peripherally grooved, as shown, and said grooves receive pins 20, projecting inwardly

from the arms of the forked clutch-operating lever 21, which is suitably mounted at 22 on the frame of the machine. The lower end of the clutch-operating lever 21 is normally engaged by a latch 24, said latch operating to hold the clutch member 19 in a position shown in Fig. 1--i. e., disengaged from the clutch member 18. Suitable means hereinafter described and which are operated upon by the work when it is brought into operative position serve to disengage the latch 24 from the lower end of the lever 21, and when this occurs the spring 25 throws the clutch member 19 into engagement with the clutch member 18, thereby locking the shafts 10 and 16 together. The rotation of shaft 16 is now communicated to shaft 10, and the driver 6 will be reciprocated by means of the pin 11. To throw the clutch out of engagement after the shaft has made one revolution, I have provided the cam 26, which is fast upon the shaft 10 and which engages a roll 27 upon one end of the pivoted lever 28, the other end of said lever having pivoted thereto the latch 24, as illustrated. As the cam 26 rotates the roll 27 drops off from the rise thereof, thus allowing the latch-carrying lever 28 to be swung into the position shown in dotted lines, Fig. 4, under the influence of a suitable spring 30. When this occurs, the end of the latch 24 is carried under the end of the clutch-operating lever 21, so that the shoulder 34 on said latch engages the pointed end of the said clutch-operating lever, the latch being held in this position by means of a spring 33. As the shaft 10 completes its reciprocation the rise of the cam 26 passes under the roll 27 and swings the lever 28 into the position shown in Fig. 1, and the shouldered latch 24 carried thereby operates to simultaneously turn the clutch-operating lever 21 to cause the clutch members to be disengaged. The driver-reciprocating mechanism now stops, although the shaft 16 is continuously rotated. Preferably I will provide a suitable tension device 40, which engages the back side of the disk 9, said tension device operating to overcome the inertia of the parts and cause the disk 9 to stop as soon as the clutch members are disengaged. The tension device may be of any suitable construction; but I have herein illustrated one comprising a pad having a stem 41 slidably mounted in the frame 3, the said pad being yieldingly held against the face of the disk by a spring 42. To release the latch 24 when the work is brought into operative position, I preferably make the nose 50 of my machine vertically movable in the end of the tubular portion 5 of the frame and connect to said nose the shank 51, which runs longitudinally of the said tubular portion and is guided thereby in any suitable way. The upper end of the shank 51 is bent at right angles, said right-angled portion 52 being curved around the tubular portion 5 and seated in a suitable parti-annular recess therein, and connected to said right-angled

portion is the offset 53 in position to engage the arm 54, integral with the latch 24. The nose 50 is held in its depressed or lowest position by any suitable means, such as a spring-pressed plunger 56, seated in a suitable recess in the frame and bearing against the upper end of the shank 51. When now the work is brought underneath the nose of the machine and pressed against the same, the upward movement of the nose will carry with it the offset portion 53, which by engaging the arm 54 of the latch will turn the same about its pivot 55 and release it from the end of the clutch-operating lever 21. The spring 25 operates to throw together the clutch member, as above described, and the driver will be reciprocated once, when the clutch members will be disengaged, as described. 85

Preferably the end of the arm 54 will have pivoted thereto a detent 60, which is freely movable in one direction, but is limited in its upward movement by a suitable stop 61. This detent allows the offset 53 to descend 90 without giving motion to the latch 24.

Suitable means are provided whereby the hopper may be rotated directly from the continuously-driven shaft 16, and the hopper-rotating mechanism is of such a character 95 that it may be disengaged when the raceway has been filled with tacks. Pivoted upon the shaft 16 is a swinging frame 70, carrying the counter-shaft 71, to which are rigidly secured the gears 72 and 73. The gear 72 meshes 100 with a gear 74, fast upon the shaft 16, while the gear 73 is so positioned as to be adapted to mesh with gear-teeth 75 on the periphery of the hopper 6'. When the frame 70 is in the position shown in Fig. 2, the gears 73 and 75 are in mesh, and the rotation of the shaft 16 will be communicated to the hopper. When it is no longer desired to rotate the hopper, the said frame 70 will be swung into dotted-line position, Fig. 2, thereby disengaging gears 110 73 and 75. The said frame 70 may be held in either desired position by means of a spring-detent 76, carried by the frame 3 and which is adapted to engage one or the other of two recesses 77 in the swinging frame. 115

Figs. 5 and 6 show my preferred form of clearer which is adapted to prevent the nails from getting lodged on the raceway. As stated above, the hopper 6' is constructed the same as in my copending application, Serial 120 No. 40,080, filed December 17, 1900, and it has on the interior thereof a series of lifting projections or shelves 80, which lift the nails and deposit them on the apron 81 of the raceway 7. Pivoted to the casting 82, which supports the hopper, as in my copending application, is a clearer 83, shown as a bent lever having an arm 84, adapted to be struck by a series of projections 85 on the hopper as the same rotates, the said projections operating 125 to vibrate the lever about its pivot 88 against the stress or tension of a spring 89. The lower end of the lever is arc-shaped and extends transversely across the raceway, said lower

end being inclined, as at 86, to correspond to the inclination of the raceway, a sufficient space being left between the lower face of the clearer and the raceway to allow the heads of such nails as are properly positioned to pass. A plurality of notches 87 are cut in the lower face of the clearer, said notches catching any nails which are improperly deposited upon the raceway and dislodging the same, thus preventing the raceway from becoming clogged. With this construction of clearer a portion of the lower curved end is always in position above the raceway, and such curved end vibrates across the raceway, as will be obvious.

Various changes may be made in the structure of the device without departing from the spirit of the invention.

Having described my invention, what I claim as new, and desire to secure by Letters Patent, is—

1. In a nailing-machine, a driver, a crank device to reciprocate the same, a continuously-rotating driving member, a clutch between said driving member and crank, a clutch-operating lever, a spring-controlled lever, a latch pivoted thereto, and engaging the clutch-operating lever to normally hold said clutch inactive, means operated by the work as it is brought into operative position to trip the latch, means to bring the clutch into action when the latch is tripped whereby the crank is rotated, a cam connected to the crank device and engaging said spring-controlled lever, said cam operating to vibrate the lever as the driver reciprocates, and bring the latch into engagement with the clutch-lever whereby the clutch is disengaged.

2. In a nailing-machine, a frame having a tubular portion, a driver reciprocating therein, driver-reciprocating mechanism including a clutch, a latch to normally hold said mechanism inactive, a movable nose at the end of the tubular part of the frame, a shank connected to said nose and extending longitudinally of the frame and guided thereby, an offset on said shank adapted to engage and trip

the latch, means to throw the clutch into operation when the latch is tripped and means to restore the clutch to its inactive position when the driver has made one reciprocation.

3. In a tacking mechanism, a driver, a raceway to deliver nails thereto, a continuously-rotating shaft to operate the driver, a rotatable hopper to deliver nails to the raceway, a swinging frame supported on the shaft, and gears on said frame adapted to mesh with gears on the shaft and hopper respectively, whereby the hopper may be rotated or allowed to remain at rest according to the position of the swinging frame.

4. In a nailing-machine, a driver, a raceway to deliver tacks thereto, a continuously-rotating shaft to operate the driver, a rotatable hopper to deliver tacks to the raceway, a gear on the shaft, and gear-teeth on the periphery of the hopper, a swinging frame supported on the shaft, connected gears carried thereby, one of said gears meshing with the gear on the shaft and the other of said gears adapted to mesh with the gear-teeth on the hopper when the frame is in one extreme position.

5. In a nailing-machine, a driver, a raceway to deliver tacks thereto, a continuously-rotating shaft to operate the driver, a rotatable hopper to deliver tacks to the raceway, a gear on the shaft, and gear-teeth on the periphery of the hopper, a swinging frame supported on the shaft, connected gears carried thereby, one of said gears meshing with the gear on the shaft and the other of said gears adapted to mesh with the gear-teeth on the hopper, and means to hold said frame either in such position that the gears on the frame and hopper will be in mesh or in such position that the said gears will be disengaged.

In testimony whereof I have signed my name to this specification in the presence of two subscribing witnesses.

PERLEY R. GLASS.
